(57) **CLAIM**

The ornamental design for the wireless communication device, as shown and described.

DESCRIPTION

FIG. 1 is a perspective view of the wireless communication device of the present invention with a portion thereof in a first position;

FIG. 2 is a top view of the wireless communication device of FIG. 1;

FIG. 3 is a bottom view of the wireless communication device of FIGS. 1 and 2;

FIG. 4 is a front view of the wireless communication device of FIGS. 1-3;

FIG. 5 is a rear view of the wireless communication device of FIGS. 1-4;

FIG. 6 is a right side view of the wireless communication device of FIGS. 1-5;

FIG. 7 is a left side view of the wireless communication device of FIGS. 1-6;

FIG. 8 is a perspective view of the wireless communication device of FIG. 1 with the portion thereof in a second position;

FIG. 9 is a top view of the wireless communication device of FIG. 8;

FIG. 10 is a bottom view of the wireless communication device of FIGS. 8 and 9;

FIG. 11 is a front view of the wireless communication device of FIGS. 8-10;

FIG. 12 is a rear view of the wireless communication device of FIGS. 8-11;

FIG. 13 is a right side view of the wireless communication device of FIGS. 8-12; and,

FIG. 14 is a left side view of the wireless communication device of FIGS. 8-13.
